UNITED STATES PATENT OFFICE.

GEORGE P. THOMAS, OF GLENSHAW, PENNSYLVANIA.

PUNCHING-MACHINE.

1,383,673.

Specification of Letters Patent. Patented July 5, 1921.

Application filed May 12, 1920. Serial No. 380,796.

To all whom it may concern:

Be it known that I, GEORGE P. THOMAS, a resident of Glenshaw, in the county of Allegheny and State of Pennsylvania, have 5 invented a new and useful Improvement in Punching-Machines, of which the following is a specification.

The invention relates to metal-punching machines, and the object thereof is to provide 10 a multiple punching machine for punching plates, such as boiler, tank, girder and like plates, whereby the time required for effecting the punching may be reduced to a minimum.

15 The invention is illustrated in the accompanying sheets of drawings, of which Figure 1 is a somewhat diagrammatic front elevation of a punching machine embodying the invention; Fig. 2 a horizontal sectional view 20 taken on the line II—II, Fig. 1; Fig. 3 a somewhat diagrammatic rear view of a portion of the machine; Fig. 4 a vertical sectional view taken on the line IV—IV, Fig. 1, the parts in Fig. 4 being shown to enlarged 25 scale and in greater detail than indicated in Figs. 1 and 3; and Fig. 5 a detached view of a detail explained hereinafter, the plane of view being indicated by the line V—V, Fig. 3.

30 The punching machine includes the usual elements common to machines of this general character, namely a frame 1, a reciprocating head 2 adapted to carry punches, and an anvil 3, attached to or forming a part of 35 the frame 1, and adapted to support dies arranged to coöperate with the punches carried by the reciprocating head.

In the practice of the invention the punching head and anvil are provided with punch 40 and die carriers equipped with a series of coöoperating punches and dies arranged in a line extending transversely of the line of feed of a blank through the punch, the carriers being laterally movable during the operation of the punch. In addition to this line of transversely extending punches and dies mounted on the movable carriers, the punching head is further provided with one or more series of coöoperating punches and 45 dies lying in a line or in lines extending parallel to the line of feed through, and immovable during the operation of the punch. Of the latter series, preferably two lines are provided, one line being adjacent to each 50 end of the transversely movable series of punches and dies. The general arrangement

is such that a transverse line of holes, either in the end of a plate or intermediate to its ends, may be punched by the transverse series of punches and dies, and that the line 60 of holes extending along the edges of the plate may be punched in multiple by the longitudinally-extending series of punches and dies. The transverse series of punches and dies are movable laterally so that a staggered 65 arrangement of end or intermediate end holes may be readily punched, and also that the end holes in a single line may be punched at closer spacing intervals than is otherwise possible by reason of the required 70 widths of the punch holders.

Referring to the illustrative embodiment of the invention, the reciprocating head 1 may be provided with a laterally movable carrier 4 provided with a T-slot 50 adapted 75 to receive a T-head 5 formed on the punching head. In a similar manner, the anvil 3 may be provided with a die carrier 6 having a depending tongue 7 extending into the slug-receiving recess of the anvil. The 80 punches 8 may be carried by holders 9 each firmly secured to the punch carrier 4, and the dies 10 may be mounted upon die holders 11 each attached to the die carrier 6. The punches and dies, as well as their respective 85 holders, and the manner of attaching the holders to their carriers, may of course vary as desired, the particular construction shown herein being merely for illustrative purposes. 90

For moving the transverse series of punches and dies laterally, the die carrier 6 may, as indicated particularly in Figs. 1 and 2, be provided with a lug 12 having a screw threaded opening adapted to receive a 95 threaded rod 13 which may be rotated by a hand wheel 14. That the die carrier 6 and punch carrier 4 may be simultaneously moved, the lug 12 may be provided with an upwardly-extending rod or boot 15 adapted 100 to be received by a guideway or shoe 16 depending from the punch carrier 4. As indicated in the drawings, a boot and shoe connection may be, and preferably is, provided between both ends of the punch and die carriers. In place of the boot and shoe construction shown herein, the punch and die carriers may be connected to each other for simultaneous movement in the manner illustrated in my pending application Serial No. 110 308,180, filed July 2, 1919. (Patent No. 1,342,879 dated June 8, 1920.)

The series of punches 17 and dies 18, parallel to the line of feed, may be mounted in suitable holders 19 and 20, respectively, the punch holder 19 being attached to the punching head and the die holder 20 attached to the anvil. Within the range of working limitations any desired number of punches and dies 17 and 18 may be arranged in series parallel to the line of feed through the 5 punch, and for punching a plate of a given width the punch holder 19 and die holder 20 may be preliminarily adjusted laterally upon the punching head and anvil so that the punches and dies will be in the proper position to punch the lines of holes adjacent to the edges of the plates. A punch holder 19 and die holder 20 may be provided at each 10 end of the transverse line of punches 8 and dies 9, as seen in Fig. 2, and such holders 15 may each be equipped with double lines of punches and dies for punching double lines 20 of holes in the side of a plate.

While the punch holder 19 may be variously attached to the punching head 1, such holder is preferably provided with a tongue 26 adapted to engage a ledge or flange 27 on the lower face of the head 1 extending transversely thereof, and bolts 28 may engage T-slots 29 formed in the side of 30 the head. The die holder 20 may be clamped in a carrier 30 by screw bolts 33, and the carrier may be clamped to the anvil 3 by bolts 32. Suitable means, such as wedges 34 may be provided for adjusting the position of the die holders so that the dies will 35 accurately register with the punches.

At the rear of the transverse line of punches 8 and dies 10 there is provided a stripper 35 attached to the lower ends of 40 rods 36 supported by the punch frame 1. For stripping from the parallel lines of punches 17 a stripper having fingers 37 may be attached to the top of the die carrier 30 in the manner indicated in Figs. 3 and 5.

45 Instead of attaching the punch carriers 4 and 19 to the main body of the punching head 1, such head is preferably provided with a facing block 38 of the general shape indicated in Fig. 3, such block being attached to the punching head by means of 50 screw bolts 39 and 40.

In operation, the line of feed through the punch is in the direction indicated by the 55 arrows 25 shown on Figs. 2 and 4. The transverse line of holes in the ends or intermediate the ends of the plate are punched by the transverse lines of punches and dies 8 and 10. When the required spacing of 60 the transverse line of holes is so small that the holes cannot, by reason of the minimum possible spacing of the punch holders, all be punched simultaneously, or when there are so many holes in the transverse lines that the punch is not powerful enough to punch 65 them all at one stroke, or when a staggered

arrangement of transverse holes is required, certain of the holes may be punched at one stroke of the punch, and, before the next stroke of the punch, the hand wheel 14 may be turned to cause the punch and die carriers 70 to move laterally to bring the punches and dies 8 and 10 in proper positions for punching other holes. After the transverse line of holes in the entering end of the plate has been punched, the plate may then be fed 75 through the punch to the position of the longitudinal series of punches 17 and dies 18 for punching the side holes in multiple groups, such punches and dies being immovable during the punching operation. 80 There thus results a very substantial saving in time of the punching operation.

I claim:—

1. In a multiple plate-punching machine, the combination of a frame provided with 85 an anvil, a reciprocating head, laterally movable punch and die carriers borne respectively by said head and anvil, means for moving said carriers laterally during the operation of the punch, said carriers being equipped with a series of coöperating punches and dies arranged in a line transverse to the line of feed through the punch for punching end and intermediate transverse lines of holes, and a series of coöperating 90 punches and dies attached to said head and arranged in a line parallel to the line of feed through said punch for punching holes in multiple in the side of a plate, said last mentioned series of punches and dies 95 being immovable during the punching operation.

2. In a multiple plate-punching machine, the combination of a frame provided with an anvil, a reciprocating head, laterally 105 movable punch and die carriers borne respectively by said head and anvil, means for moving said carriers laterally during the operation of the punch, said carriers being equipped with a series of coöperating punches and dies arranged in a line transverse to the line of feed through the punch for punching end and intermediate transverse lines of holes, and lines of punches 110 and dies arranged parallel to said line of feed one adjacent to each end of said transverse line of punches and dies, said parallel lines of punches and dies being attached to said head and anvil for punching holes in multiple in the sides of a plate, said last 115 mentioned lines of punches and dies being immovable during the punching operation.

3. In a multiple plate-punching machine, the combination of a frame provided with an anvil, a reciprocating head, laterally 125 movable punch and die carriers borne respectively by said head and anvil, means for moving said carriers laterally during the operation of the punch, said carriers being equipped with a series of coöperating 130

punches and dies arranged in a line trans-
verse to the line of feed through the punch,
a stripper for said punches at the rear of
the line thereof, punch and die carriers at
5 the rear of said transverse line of punches
and dies and equipped with coöperating
punches and dies arranged in a line parallel
to the line of feed through the punch, and a
stripper attached to said last-mentioned die

carrier for stripping from said last men- 10
tioned punches.

In testimony whereof, I have hereunto
set my hand.

GEORGE P. THOMAS.
